FORM CLAMP

Filed Dec. 19, 1930

UNITED STATES PATENT OFFICE

GEORGE B. BOSCO, OF CHICAGO, ILLINOIS

FORM CLAMP

Application filed December 19, 1930. Serial No. 503,371.

My present invention relates to improvements in form clamps or instrumentalities for drawing and holding forms for casting concrete in position to receive the concrete. 5 It is now, and has for sometime past been, regarded as desirable, and sometimes necessary, to cast about the metal elements of structures having a metal frame work, a casing of concrete for heat insulation or fire 10 protection and other purposes.

My present invention has special relation to improvements in the instrumentalities for hanging forms from and about horizontally disposed elements such as beams and girders 15 and constitutes an extension and simplification and improvement of the practices and devices illustrated in Figs. 2 and 5 of Patent No. 1,475,424 issued to me November 27, 1923, and in Figs. 1, 3 and 5 of Patent No. 1,515,- 20 385 issued to me November 11, 1924.

In the first of the foregoing patents I illustrated how a form could be hung from and drawn in position around a beam when the structure was such as to permit convenient 25 access to the bottom of the form for operating the facilities which I provide.

In the second of the above mentioned 30 patents I illustrated how a form could be hung from and drawn about a beam when circumstances permitted a more ready access to the top of the beam than to the bottom of the form which is more usually the case.

The instrumentalities for securing the 35 above results shown in the aforementioned patents comprise band iron with instrumentalities for exerting the necessary pull thereon and securing it in place after it has been properly adjusted.

My present invention consists of an improvement in the facilities for permitting the 40 band iron to be pulled in desired position and securing it in such position when attained.

My present invention secures a considerable 45 simplification of such instrumentalities which attains a much desired economy and which also is much easier and quicker put in position and use as it requires no threading of the band iron into the clamp, which 50 is an annoying and time consuming opera-

tion if the band iron be bent or distorted, and it is well nigh impossible to get a piece of band iron in position without imparting to it undesired and undesirable bends. By 55 overcoming the necessity of threading the band through apertures in the clamp the use of my invention secures a substantial saving in the time of installation.

I have attained the foregoing objects and results by means of the structure illustrated 60 in the accompanying drawings in which—

Fig. 1 is a schematic illustration in section of a form hung to and about an I-beam employing my improved form clamp adapted to receive and hold both ends of the loop of 65 band iron.

Fig. 2 is a plan of the construction shown in Fig. 1.

Fig. 3 is a view similar to that shown in Fig. 1 in which the clamp is modified slightly so as to hold but one end of the band iron. 70

Fig. 4 is a plan of the structure shown in Fig. 3.

Fig. 5 is a perspective of the clamp shown in Figs. 1 and 2. 75

Fig. 6 is a perspective of the clamp shown in Figs. 3 and 4.

Similar reference characters refer to similar parts throughout the respective views. 80

What is required is to draw a form in position and support it with respect to the I-beam 10 so that it can receive and hold the concrete 11. I-beams employed in ordinary building construction vary considerably in size, and what is important in this consideration the flanges in such I-beams vary in thickness from one-half inch to two inches. The variation may be greater than above stated, but the above statement covers the usual and ordinary practice. 85

The forms are long trough-like structures comprising a bottom 12 and sides 13 and 14. At requisite intervals to secure the necessary stability cross-braces 15 are secured transversely of the bottom, and side braces 16 and 90 17 are provided for strengthening the sides. To space the bottom of the form from the bottom flange of the beam are provided form nails 18, or other suitable spacing elements, and the bottom of the form is usually pierced 100

or apertured, as at 19, at suitable intervals for threading up the ends of a loop of band iron 20. This much of the work is usually performed before the assembly with the I-beam is commenced.

My form clamp comprises a rectangular body portion 21 of sufficient width to accommodate the width of one or two strips of band iron, as the case may be, from one end of which laterally extend wing-like developments 22 which are bent upwardly with respect to the body portion, preferably at 90° or more from their original position in the blank but not so far as to bring the upwardly extending ends of these wings too close together to prevent the laying or entry of a strip of band iron therebetween. When the body portion is of a width to accommodate two strips of band iron side by side the end 20 of the body portion of the clamp opposite to that from which the wings or developments 22 extend is bent at right angles downwardly, as at 23, or in the opposite direction to the bending of the wings 22 for the purpose of abutting the edge of a flange of the I-beam 10.

For assembling the form with the I-beam the clamp as above described is placed on the top flange of the I-beam between the upwardly extending ends of the loop 20 of band metal with the depending end 23 abutting the edge of the flange. The ends of the loop of band iron are then folded over the top of the beam from opposite directions and enter 35 between the upstanding wings 22 of the clamp and are located between the wings side by side. The wings 22 are then hammered down to engage the strips of band iron.

The pulling-up tool 24 is then employed 40 for tightening the band iron until the form is hung in proper relation to the I-beam. The grip of the turned down wings 22 on the band iron is sufficient to support the weight of the form when empty, but is not sufficient to interfere with the drawing of the band iron with the pulling-up tool. When the form has been drawn into desired position with 45 reference to the beam the ends of the band iron are bent back and hammered down over the tops of the wings 22, as at 25. When so bent back and employing a clamp made from 50 12 gauge metal a force of 4000 pounds can be exerted in the pulling-up of the band iron and will be held by the clamp, which is ample 55 to support the weight of the form when filled with concrete.

It will be noted that the end of the band iron passing down over depending end 23 of the clamp in association with the pull of the 60 end of the band iron extending in the opposite direction will permanently and dependably fix the relation of the clamp to the beam.

The clamp designed for accommodating a single width of band iron, as shown in Figs. 65 3, 4 and 6, differs only from the wider form

in width and in extending the depending end flange 23 and bending the same backwardly, as at 26, to engage the under side of the flange of the I-beam, because, in this form, there is no length of band iron for holding the flange 23 to the beam. In the single form the flange 23 and turned back end 26 may be centrally corrugated or beaded, as at 27, to somewhat stiffen the structure without additional expense. 70

The simplicity of the present clamp in connection with the ease of associating the band iron with it secures substantial economies. The possibility of pulling up the band iron with the pulling-up tool after the band iron is engaged by the clamp assists in quickly securing the final desired adjustment, and it will further be noted that there is no danger of shearing the band iron which must be guarded against when a wedge or wedge-like action is employed in finally securing the band iron to the clamp. 80

Having described my invention what I claim as new and desire to secure by Letters Patent is:

1. A form clamp for use in association with band iron and a pulling-up tool comprising a blank of metal, an integral flange depending from one end thereof, wings extending from the sides of said blank at the end opposite said flange, said wings being bent upwardly so as to receive strips of band iron therebetween and adapted to be flattened down upon the included band iron, whereby said band iron may be tightened after assembly with 95 said clamp through the instrumentalities of said pulling-up tool and said depending flange. 100

2. A form clamp for use in association with band iron and a pulling-up tool comprising a blank of metal, an integral flange depending from one end thereof, wings extending from the sides of said blank at the end opposite said flange, said wings being bent upwardly so as to receive a portion of a 105 loop of band iron therebetween and adapted to be flattened down upon the included band iron, whereby said band iron may be tightened after assembly with said clamp through the instrumentalities of said pulling-up tool 110 and said depending flange. 115

GEORGE B. BOSCO.
